UNITED STATES PATENT OFFICE.

THOMAS SLOPER, OF DEVIZES, ENGLAND.

MANUFACTURE OR TREATMENT OF LENGTHS OF CORD OR OTHER MATERIAL.

965,240.

Specification of Letters Patent. Patented July 26, 1910.

Application filed June 3, 1909. Serial No. 500,026.

To all whom it may concern:

Be it known that I, THOMAS SLOPER, a subject of the King of England, residing at Devizes, in Wiltshire, England, have invented certain new and useful Improvements in the Manufacture or Treatment of Lengths of Cord or other Material, of which the following is a specification.

This invention is for improvements in or relating to the manufacture or treatment of lengths of cord or other material and has for its main object to provide mechanism whereby the cord or other strip of material while under treatment may be maintained under uniform tension.

The invention is particularly applicable to the manufacture or treatment of rubbered cords such as are used in the manufacture of cord tires, although the invention is not restricted to this. The rubbered cords referred to are conveniently first made of circular cross section and then flattened so that the cross section is oblong. To flatten the cord it may be passed between rollers and received on a bobbin and during this operation of winding on to the bobbin it is particularly desirable to maintain that portion of the cord which lies between the receiving bobbin and the rollers under a uniform tension. Similarly it is necessary sometimes to wind the cord from one bobbin to another apart from flattening, and when doing this it is required to keep the cord under uniform tension. Heretofore these winding operations have been effected by means of a slipping clutch or belt employed for driving the bobbin so that when the tension on the cord being wound became too great owing to the "take-up" being in excess of the feed, the clutch or belt would slip or increase its slip. Such an arrangement is very crude and by it the cord is subjected to considerably varying strains as it is impossible in practice to so arrange the "feed" mechanism (in this case the flattening rolls) and "take-up" mechanism that they exactly synchronize, and moreover the rate of "take-up" increases as the bobbin becomes full. To maintain the tension on the cord under treatment constant, it is therefore necessary to introduce some device which is extremely sensitive so that the least change of tension may be immedi-

ately rectified and thus what may be termed a uniform tension maintained.

According to this invention a friction drive for the bobbin or other suitable part of the machine is used as before, but in conjunction with it mechanism is employed for varying the degree of pressure of one driving member against the other for the purpose of maintaining the tension upon the cord constant as it is fed through the machine. Preferably the mechanism employed with the friction drive is controlled by the tension put upon the cord as it is fed through the machine in such manner that it varies the degree of pressure of one driving member against the other, and thus, by continually correcting any slight momentary variation of tension, maintains generally speaking a uniform tension on the cord.

According to one method of carrying out this invention, the mechanism for controlling the friction drive comprises a jockey-pulley, carried by a yielding support, and over which the cord is passed as it travels from the flattening rolls to the receiving bobbin. The yielding support is operatively connected with the friction drive so that as the length of cord feeding through the machine decreases or increases owing to variations in the rate of operation of the feed rolls and the bobbin, the pulley will be displaced and correspondingly regulate the friction drive. The friction drive may comprise two opposed disks, one of which is spring-controlled and the movements of the jockey-pulley may control the pressure of the spring so as to decrease the pressure of the corresponding friction member against the opposed member as further slip is required. With the same machine there is preferably provided a gaging arm over which the cord is passed so that should a knot or unduly large portion occur in the cord such portion will be unable to pass the arm. The arm is operatively connected with a clutch and when any part of the cord is unable to pass it the arm is pulled over by means of the cord and disconnecting the clutch stops the machine.

In the accompanying drawings:—Figure 1 shows diagrammatically a machine constructed according to one method of carrying out this invention, and Fig. 2 shows

diagrammatically the same machine viewed from the right of Fig. 1.

Like letters indicate like parts throughout the drawings.

- 5 The cord A on the supply bobbin B is of circular cross-section but after passing between the flattening rollers C its shape is altered so that the cross-section is oblong and it is then wound on to the receiving 10 bobbin D. The bobbin B may be free upon its spindle but the bobbin D is driven by a friction clutch comprising a driving disk E and a driven disk E¹. The driving disk is fast upon a shaft E² that may receive its 15 motion by means of a chain and sprocket wheels from an intermediate shaft F. Free on the shaft F is a worm-wheel F¹ that is driven by a worm G and on one side of the worm-wheel is a clutch-part F² which co- 20 operates with a sliding clutch-part F³. The shaft F carries one of the flattening rollers C and is geared by means of wheels H to a counter-shaft H¹ which carries the other flattening roll C.
- 25 Secured to a rocking shaft J that is pivoted near the rollers C is an arm J¹ carrying a guide roller J² and gaging finger J³. The rocking shaft J has on it an arm J⁴. This arm is connected at J⁵ to an arm J⁶. An 30 other rocking shaft J⁷ and an arm J⁸ on this second rocking shaft has engagement with the clutch member F³. The rocking shaft J⁷ also carries a third arm J⁹ that is engaged by a spring-controlled or locking arm J¹⁰ 35 having two notches J¹¹ and J¹² respectively. The cord as it leaves the bobbin B is passed over the guide roller J² and between it and the gaging finger J³. It then passes between the flattening rollers C and is carried over a 40 jockey-pulley K. The spindle of this pulley is carried by an arm K¹ which in turn is supported by a chain or cord K² that lies over a wheel L and has at its other end a counterbalance-weight K³. The weight K³ 45 is heavier than the pulley K so that it maintains a slight tension upon the cord. The wheel L is free on its spindle but has fast upon it a chain wheel L¹. This wheel is connected by a chain L² to a chain wheel L³.
- 50 The wheel L³ carries a cam L⁴ and bearing against the cam is an arm M. This arm is pivoted at M¹ to a fixed support and has connection at M² with the driven friction disk E¹ that is free to slide on the shaft E³.
- 55 A spring E⁴ acts to hold the friction disk E¹ against the disk E, and also to hold the arm M against cam L⁴. The shaft E³ carries the bobbin D but is so connected with the sliding disk that the two members must rotate together.
- 60 After leaving the jockey-pulley K the cord passes over guide pulleys N N¹ carried by a traversing arm N² that is pivoted at N³. The arm is controlled by reciprocating mechanism N⁴ having a right- and left-hand screw whereby the arm is moved

backward and forward to feed the cord on to the bobbin. This mechanism is of a well-known type and therefore does not require detailed description, as it forms no part of the present invention.

The operation of this machine is as follows:—The feed rolls C draw the cord from the supply bobbin B but before entering the rollers the cord passes between the gaging members J² J³. If a knot or undue 70 enlargement occurs on the cord which will not pass the gaging members, the arm J¹ is by means of the cord swung toward the feed rollers and through the medium of the rocking shaft J and its connection with the rocking shaft J⁷ causes the clutch member F³ to be drawn away from the member F². This stops the whole machine and calls attention to the fault. The detent arm J¹⁰ 75 by means of its notch J¹¹ holds the arm J⁹ normally in such position that the clutch F² F³ is operative, but when the clutch is disconnected the arm J⁹ is moved into the second notch J¹² and held in this position by the detent lever. Provided there are no 80 knots or lumps the cord passes freely between the gaging members and being flattened between the rolls passes over the jockey-pulley down to the bobbin D on to which it is guided by the traverse lever N² 85 and its guide pulleys N N¹. The bobbin D however has to be driven in order that the cord may be wound thereon and requires to be driven at such a speed that it will always take up the cord as it is fed from the rollers. 90 As the diameter of the bobbin is continually changing owing to the building up of the cord thereon it is necessary that some device for varying the speed of rotation must be introduced. An ordinary friction drive is 95 very inefficient for this purpose as such devices are very irregular in action and if the bobbin were driven by one of these the cord would be subjected to varying tensions, whereas it is desired that the tension 100 shall be uniform. With the arrangement shown the tension on the cord is always maintained uniform, as an increased rate of feed on to the bobbin D, as for instance 105 when the bobbin is partially full, causes 110 more slack to be taken up between it and the feed rolls and this draws down the jockey-pulley K against the action of the counterbalance-weight K³. The movement 115 of the jockey-pulley downward rotates the wheel L in the direction indicated by the arrow and this in turn rotates the wheel L³ and the cam L⁴ in the same direction. The cam L⁴ thus pushes back the lever M against 120 the action of the clutch spring E⁴ and thereby eases the pressure of the friction disk E¹ upon the disk E. This causes an increase 125 of slip to occur between the two members so that the bobbin D is driven more slowly. It will be seen that the adjustment is quite 130

automatic and that the clutch E E¹ may be made extremely sensitive as a given displacement of the jockey-pulley K may be made to produce any desired displacement 5 of the friction member E¹ by varying the ratio of the gears L¹ L³ and the shape of the cam L⁴.

Instead of the wheel L obviously a counter-balance-arm may be employed, but the wheel 10 is preferred as by using a chain or other comparatively heavy flexible connection between the jockey-pulley K and the weight K³, the weight of the chain may be made to approximately counter-balance the increasing 15 or decreasing resistance offered by the cam L⁴, lever M, and spring E⁴. It will be seen that if the wheel L is rotating in the direction indicated by the arrow, the length of chain is increasing on the right hand side 20 of the wheel and therefore tends to aid the rotation of the wheel. On the other hand the cam L⁴ is offering increased resistance to this movement as owing to its eccentricity the lever M tends to rotate it in the opposite 25 direction. The chain thus approximately counter-balances the increased resistance offered by the cam and when the direction of movement is reversed the length of chain on the right hand side of the wheel 30 helps to counter-balance the tendency of the cam L⁴ to rotate in a counter-clockwise direction under the action of the lever M and spring E⁴.

Although this invention has been described as applied for flattening rubbered cords it can obviously be employed wherever it is required to wind a cord or strip of any material from one bobbin to another, or from any form of feed mechanism on to a 40 receiving bobbin.

What I claim as my invention and desire to secure by Letters Patent is:—

1. In a machine for the manufacture or treatment of lengths of material the combination of, a receiving bobbin, a driving member, a driven member having frictional engagement with the driving member and that is operatively connected with the receiving bobbin, means independent of said 45 bobbin for feeding material thereto, and means controlled by the material as it is fed through the machine to vary the pressure of one friction member against the other in proportion to any variation of tension on the material in the machine and for the purpose of correcting such variation, substantially as set forth.

2. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, engaging 60

means for forcing one friction member into engagement with the other, a device for taking up any slack in that portion of the material that lies between the positive feed device and the receiving bobbin and that co-operates 70 with the aforesaid engaging means for the friction driving members in such manner as to vary the pressure of one friction member upon the other in proportion to the amount of slack taken up at any given time, for the 75 purpose of maintaining the tension on the material constant, substantially as set forth.

3. In a machine for the manufacture or treatment of lengths of material the combination of, a receiving bobbin, a positive feed 80 device for supplying the material to the bobbin, a driving member, a driven member having frictional engagement with the driving member and that is operatively connected with the receiving bobbin, a device 85 for taking up any slack in that portion of the material that lies between the positive feed device and the receiving bobbin and that is operatively connected with one of the friction driving members in such manner as to vary the pressure of one member upon the other in proportion to the amount of slack taken up at any given time, for the 90 purpose of maintaining the tension on the material constant, substantially as set forth. 95

4. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, engaging means for forcing one friction member into engagement with the other, a guide around 100 which a bend of that portion of the material that lies between the positive feed device and the receiving bobbin is passed, a tension device that always tends to displace the guide in such direction as to take up 110 any slack in the bend of the material, and means controlled by the guide and co-operating with the aforesaid engaging means for the friction driving members in such manner as to vary the pressure of one friction member against the other as the guide moves in one direction or the other according to the increase or decrease in length of the bend of material passing around it, substantially 115 as and for the purpose set forth. 120

5. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, engaging means for forcing one friction member into engagement with the other, a jockey-pulley 125 130

around which a bend of that portion of the material that lies between the positive feed device and the receiving bobbin is passed, a counter-balanced arm that carries the jockey-pulley and whose counter-balance is sufficient to always tend to move the jockey-pulley in such a direction as to draw upon the bend of the material, and means controlled by the jockey-pulley and coöperating 5 with the aforesaid engaging means for the friction driving members in such manner as to vary the pressure of one member against the other as the jockey-pulley moves in one direction or the other according to the increase or decrease in length of the bend of material passing around it, substantially as and for the purpose set forth.

6. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, engaging means for forcing one friction member into engagement with the other, a jockey-pulley around which a bend of that portion of the material that lies between the positive feed 20 device and the receiving bobbin is passed, a wheel over which a flexible connector lies one end of which carries the jockey-pulley and the other a counter-balance, such counter-balance being sufficient to always tend 25 to move the jockey-pulley in such direction as to draw upon the bend of material passed around it, and means controlled by the wheel and coöperating with the aforesaid engaging means for the friction driving members in such manner as to vary the pressure of one member against the other as the jockey-pulley moves in one direction or the other according to the increase or decrease in length of the bend of material 30 passing around it, substantially as and for the purpose set forth.

7. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, engaging 35 means for forcing one friction member into engagement with the other, a jockey-pulley around which a bend of that portion of the material that lies between the positive feed device and the receiving bobbin is passed, a wheel over which a flexible connector of heavy material is passed the connector supporting at one end the jockey-pulley and at the other and on the opposite side of the wheel a counter-balance, a cam shaft, means 40 for operatively connecting the wheel with

the cam shaft, a yieldingly controlled member that bears against the cam of the cam shaft and coöperates with the aforesaid engaging means for the friction driving members in such manner as to vary the pressure 70 of one member against the other when it is displaced by the cam, the arrangement of the parts being such that when the cam is displacing the member against its yielding control the longer and consequently heavier 75 portion of the flexible connection is on that side of its supporting wheel which tends to move the cam in the direction it is to be moved, for the purpose set forth.

8. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, a counter-balanced device for taking up any slack in that portion of the material that lies between the positive feed device and the winding bobbin, yielding means whereby one friction driving member is maintained in engagement with the other friction driving member, and means whereby the said device for taking up the slack is made to vary the effective force of the yielding control, for the purpose set forth.

9. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, a device 100 for taking up any slack in that portion of the material that lies between the positive feed device and the receiving bobbin, a cam, means for operatively connecting the jockey-pulley with the cam in such manner that the movements of the former for taking up the slack will rotate the cam, yielding engaging means whereby one friction driving member is maintained in engagement with the other friction driving member, and means 105 operated by the cam for varying the degree of pressure of one friction member upon the other, for the purpose set forth.

10. In a machine for the manufacture or treatment of lengths of material the combination of, a receiving bobbin, a positive feed device for supplying the material to the bobbin, a driving member, a driven member having frictional engagement with the driving member and that is operatively connected with the receiving bobbin, engaging means for forcing one friction member into engagement with the other, a device for taking up any slack in that portion of the material that lies between the positive feed 120

115

125

130

device and the receiving bobbin and that cooperates with the aforesaid engaging means for the friction driving members in such manner as to vary the pressure of one member against the other in proportion to the amount of slack taken up at any given time for the purpose of maintaining the tension on the material constant, a gaging device through which the material is passed prior to its admission to the positive feed device, means for supporting the gaging device in such manner that it can be displaced by the material should any part of the material be too large for the gage, and means operatively connecting the gaging device with the driving mechanism of the machine in such manner that the machine is stopped if the gaging device is displaced.

10 11. In a machine for the manufacture or treatment of lengths of material the combination of, a receiving bobbin, opposed rollers whereby the material is fed to the bobbin and which flatten the material as it passes between them, a driving mem-

ber, a driven member having frictional engagement with the driving member and that is operatively connected with the receiving bobbin, engaging means for forcing one friction member into engagement with the other, and a device for taking up any slack in that portion of the material that lies between the flattening rollers and the receiving bobbin and that cooperates with the aforesaid engaging means for the friction driving members in such manner as to vary the pressure of one member against the other in proportion to the amount of slack taken up at any given time for the purpose of maintaining the tension upon the material constant, substantially as set forth.
